UNITED STATES PATENT OFFICE.

SAMUEL ALTMAN AND JOSEPH GROSSMAN, OF NEW YORK, N. Y.

WASHBOARD.

Specification of Letters Patent. Patented Feb. 24, 1920.

1,331,890.

Application filed October 8, 1919. Serial No. 329,401.

To all whom it may concern:

Be it known that we, SAMUEL ALTMAN, a citizen of Russia, and residing at New York, in the county of Bronx and State of New York, and JOSEPH GROSSMAN, a citizen of the United States, and residing at New York, in the county of New York and State of New York, have invented new and useful Improvements in Washboards, of which the following is a specification.

This invention relates to wash-boards, and the principal object is the provision of an improved construction, provided above the rubbing board or brand with a receptacle for holding articles such as soap, the bottom of the receptacle being holed through to permit the quick escape of water draining from the soap or similar articles when in use, the front wall of the receptacle consisting of doors, adapted to slide upon each other to permit access to the receptacle. In this connection also, there is in view the provision of a metallic wash-board having its parts so designed that it may be manufactured at comparatively small expense.

Other improvements are referred to in detail hereinafter.

The accompanying drawings illustrate the preferred embodiments of the invention as reduced to practice.

Figure 1 is a view in front elevation of a wash-board made in accordance with the present invention.

Fig. 2 is a longitudinal section, taken on the line 2—2 of Fig. 1.

Fig. 3 is a similar section, fractionally shown, on a larger scale.

Fig. 4 is a horizontal section, taken on the line 4—4 of Fig. 1.

Referring more particularly to the embodiments illustrated, the numerals 5 and 6 represent corresponding side-bars or legs, which are connected at their top ends by a head-bar 7. These parts are made of metal, preferably of comparatively thick sheet tin, which is curved upon itself, by any suitable operation, into tubular form. Each side-bar, at a suitable and corresponding distance above its foot end, has its longitudinal meeting edges cut away so as to provide a longitudinal slot 8.

9 represents a metallic corrugated rubbing plate or brand, which is engaged between the side-bars 5 and 6, its side edges extending through the slots 8 formed there-

in. The lower end 10 of the rubbing plate is curled around and clenched upon a rod 11, which extends through and connects the side-bars, the outer ends of the rod being massed or spread to form securing rivet heads 12. As clearly shown in Fig. 3, the top end of the rubbing plate, between the side-bars, is bent upon itself to form two parallel upwardly projecting ridges 13 with a furrow therebetween, and is then crimped upon itself. This same figure also shows that the head-bar 7 is made with two parallel downwardly projecting ridges 14 with a furrow therebetween. Arranged, one behind the other, in the furrows or grooves thus made in the rubbing plate and head-bar are the sliding doors 15 and 16, each of which is just a little longer than one-half the distance between the side-bars. Each sliding door, near its outer end, is provided with a finger aperture 17, by which it may be conveniently opened or closed in an obvious manner. To brace the rubbing plate and head-bar, we connect the rear ridges thereof, midway their lengths, by a strip 18.

As best shown in Fig. 4, there are secured by soldering or otherwise, in the side-bar slots 8, between the rubbing plate and the head-bar, the elements 19, approximately U-shaped in cross-section, and positioned with their furrows confronting to receive the outer ends of the sliding doors when closed. The sliding doors represent the front closure or plates for a rectangular receptacle 20, whose top plate 21 is soldered or otherwise secured to the head-bar 7, whose bottom plate 22 is similarly secured to the rubbing plate, and whose opposite end plates are secured in like manner to the adjacent side-bars. This receptacle is designed to hold soap cakes, soap powder, bluing, and other materials used in washing. In the commonly constructed wash-boards, the soap ledge is so narrow that the soap cakes are continually slipping or falling off when wet. Moreover, they are held in such position that the arms and sleeves of the washer are continually being daubed with the soap. Through the introduction of our door closed receptacle, these disadvantages are eliminated.

The bottom plate 22 is provided with a series of apertures 24, for the quick escape of any water that is carried into the receptacle on the soap cakes. The soap cakes,

therefore, being located in a dry place when not in use, are not wasted, a feature which marks another advantage over the commonly employed wash-boards.

5 Inserted in the lower ends of the side-bars are suitable feet 25, on which the structure rests, the same being preferably of tubular form to permit the water to drain from the side-bars, which are also provided with other water outlets 26.

10 Having thus described our invention, what we claim is:

In a wash-board, a frame consisting of tubular side-bars and a tubular head-bar engaged therebetween, said head-bar being 15 formed with parallel downwardly project-

ing ridges to form a groove, a rubbing plate engaged between the side-bars and having its top end formed with parallel upwardly projecting ridges to form a groove, door elements slidably engaged in said head-bar groove and in said rubbing plate groove, members carried by the side-bars for receiving the outer ends of the door elements when closed, and a receptacle supported by 20 the structure behind the door elements for holding washing materials.

25 In testimony whereof we have signed our names to this specification.

SAM ALTMAN.
JOSEPH GROSSMAN.
